UNITED STATES PATENT OFFICE.

ALBERT F. LUCAS, OF TOLEDO, IOWA.

LUMBER-LOADING DEVICE.

SPECIFICATION forming part of Letters Patent No. 758,989, dated May 3, 1904.

Application filed January 19, 1904. Serial No. 189,687. (No model.)

To all whom it may concern:

Be it known that I, ALBERT F. LUCAS, a citizen of the United States, residing at Toledo, in the county of Tama and State of Iowa, have 5 invented certain new and useful Improvements in Lumber-Loading Devices, of which the following is a specification.

The object of this invention is to facilitate the loading and unloading of lumber in and 10 from cars; and the invention consists in an adjustable roller and mounting therefor adapted to be conveniently attached to the side or end of the car below the door or window, as will be more particularly set forth in the description 15 and claim following.

In the accompanying drawings, forming a part of this specification, Figure 1 is a view of the device in perspective as applied to the end of a car. Fig. 2 is a rear view of the same. 20 Fig. 3 is a central vertical section of Fig. 2. Fig. 4 is a fragmentary top view of the roll-supporting frame.

As ordinarily performed the loading and unloading of cars with lumber is a laborious operation, especially in the case of heavy timbers, as usually the material must be passed 25 through the window at the end of the car and slid bodily along the sill. It is usually necessary, too, to pass it out at an angle to the car in unloading, owing to the difficulty of placing a wagon at the end of a car, and the wagon must accordingly stand alongside the track at the rear of the car. This invention is designed to lighten much of this labor by 30 providing rollers to carry and guide the lumber either straight out from the car or at an angle thereto.

In the drawings, A designates a part of a freight-car of an ordinary type provided with 35 the usual window B at the end and a track C to carry the door D, closing said window.

E is a rectangular iron frame provided with 40 a pair of adjustable hooks F, secured thereto

by bolts G. By this means the position of the frame may be adjusted up or down, so as 45 to bring the roller (presently to be described) to the proper level with respect to the window-sill. It is to be understood that the relative position of the door-carrying rail varies to some extent in different cars. Hence the 50 necessity for this adjustment. At some distance from the top of the frame is a cross-bar H, and to the top of the frame is secured, as by rivets I, a plate J, provided with a number of holes K to take studs L on the under 55 side of a roll-carrier M. This has a stem N, passing through the top of the frame and the cross-bar, as shown. Between the upwardly-extending arms of the roll-carrier and journaled in them is a roller O, normally horizontal. In suitable openings P in the same 60 arms are journaled short vertical rollers Q to serve as antifriction-guides for the sides or edges of the lumber passed over the longer roller. It will be seen that the long roller 65 may be set parallel with the top of its supporting-frame at an angle thereto in either direction for convenience in passing lumber.

Having thus described my invention, what I claim as new, and desire to secure by Letters 70 Patent, is—

The combination with a supporting-frame provided with adjustable hooks and an adjusting-plate, substantially as described, of a roll-carrier pivotally mounted in said frame, and 75 having depending studs to engage the plate adjustably, a horizontal roller journaled in its vertical arms, and a vertical roller journaled in each arm.

In testimony whereof I affix my signature in 80 presence of two witnesses.

ALBERT F. LUCAS.
